FRACTURE REDUCING SPLINT

Creed A. Wiltrot, Thief River Falls, Minn., assignor to himself and Alvina P. Wiltrot, Thief River Falls, Minn.

Application June 19, 1934, Serial No. 731,269

6 Claims. (Cl. 128—85)

The present invention appertains to new and useful improvements in surgical appliances and more particularly to a novel leg fracture reducing splint, of the type wherein the splint involves anchoring means for attachment to a sound leg and tensioning means between the anchoring and the splint unit which is attached to the fractured leg, for exerting a pull on the fractured leg to reduce the fracture and hold this fractured leg in extended position and in companionship with the sound leg.

The principal object of the present invention is to provide a fracture reducing splint of the type specified wherein a scale is associated with the spring so that the tension being exerted on the fractured leg can readily be determined.

Another important object of the present invention is to provide a fracture reducing splint of the type specified wherein the parts are made compact and do not extend a prohibitive distance beyond the feet to bear against the foot of a bed or other structure, which inconvenience is prevalent in several types now on the market.

During the course of the following specification and claims, other important objects and advantages of the invention will become apparent to the reader.

In the drawings:

Figure 1 is a fragmentary detailed sectional view, showing the apparatus in front elevation and the casts on the legs in section.

Figure 2 is a sectional view taken substantially on line 2—2 of Figure 1.

Figure 3 is a vertical sectional view through the splint feature.

Figure 4 is a longitudinal sectional view through the tensioning means and scale.

Figure 5 is an elevational view of the feed nut for the tensioning means.

Figure 6 represents multiple perspective views of the four major parts of the apparatus.

Figure 7 is a cross sectional view taken substantially on line 7—7 of Figure 4.

Figure 8 is a fragmentary perspective view showing the scales barrel of the tensioning means.

Referring to the drawings wherein like numerals designate like parts, it can be seen, in Figure 1, that numeral 5 represents the lower portion of a human body, with numeral 6 designating the usual pelvis bone with the leg bones 7 attached thereto.

Reference character *a* represents the good leg in the drawings, while reference character *b* represents the fractured leg.

A full description of the apparatus will now be

given before description of the operation and application thereof is afforded.

By referring to Figure 6 and also to Figure 1, it can be seen that the apparatus consists of an anchor which involves a bar 8 having an ankle receiving offset 9 therein. A short extension 10 is attached as at 11 to the bar 8 and is provided with an L member 12 having an opening 13 at its outer end. A cross member 14 is attached to the inside of the bar 8 just below the ankle receiving offset 9.

The bar 8 which in fact is preferably of strap iron material is twisted at right angles at its lower end and bent backwardly to form a saddle 15. Numeral 16 represents the swingable lever having 15 the apertured head 17 at one end for disposition in the saddle 15. A pin or bolt 18 extends through the apertured saddle 15 and the apertured head 17 for pivotally connecting the lever 16 to the anchor bar 8.

The opposite end of the lever 16 is twisted to a right angular position and rolled backwardly to form the short barrel 19. The barrel 19 fits between the depending leg portions of the inverted U-shaped member 20, the bight portion of which is provided with a segmental shaped plate 21 of about ninety degrees, the same being provided with an arcuate slot 22 adjacent the curved edge thereof.

Numeral 23 represents an enlarged U-shaped splint structure, the same being provided with the bight 23' having a block 24 secured upon the same and a central aperture 25 extending through the bight and the block 24 for receiving the bolt 26 which also extends through the opening 27 in the U-shaped member 20. In this manner the splint 23 proper is rotatably mounted upon the U-shaped connector 20 and it will be observed in Figure 3 that the bolt 28 extends through the leg portions of the U-shaped connector 20 and through the short barrel 19 of the lever 16 and in this manner the lever is pivotally connected to the splint.

It will be observed in Figure 6, as well as in Figure 1, that the upper ends of the leg portions 45 of the splint 23 are curved outwardly and backwardly as at 29 and that each leg of the splint proper is provided with a row of longitudinally spaced openings 30.

The next important feature and the last involved are tensioning means, and the adjustment therefor and the scales. By referring to Figure 4 it will be seen that numeral 31 represents an elongated barrel having a pin provided lug 32 in one end, the pin 33 being adapted for disposition 50 55

through the aperture 13 of the L-member 12 on the anchor bar extension when the apparatus is set up for use.

Extending into the barrel 31 from the opposite end thereof is the elongated and threaded rod 34 having a head 35 for riding engagement in the barrel. Numeral 36 represents a flanged bushing for engagement into the last mentioned end of the barrel and through this the threaded rod 34 extends. A cagelike frame 37 is adapted to contain the coiled compressible spring 38 which at one end bears against one end of the frame 37 and at its opposite end against the bushing 36.

15 The outside of the last mentioned end portion of the barrel 31 is provided with longitudinally spaced and circumferentially extending markings or grooves 39 as well as longitudinally extending flat portions 40 on which pound-pressure readings 20 are inscribed, each circumferentially extending line or groove being interrupted by a reading or inscription. The edge portion of the frame 37 at 41 is complementary to this scale on the barrel 31.

25 A winged nut 42 feedable on the threaded rod 34 is adapted to be fed against the frame 37 for compressing the spring. Obviously the disposition of the opposite end of the frame 37 with respect to the scale readings on the barrel 31 will 30 determine the pound-pressure the spring is exerting on the lever 16 in reducing the fracture.

35 A yoke 43 at the outer end of the threaded rod 34 engages over the lever 16 and a pin is disposed through the yoke and the opening 44 of the lever for pivotally connecting the yoke and lever together.

In applying the apparatus, the anchor bar 8 is held in place on the good leg *a* by the cast 45 so that the saddle 15 will project beyond the foot 40 to the limited extent shown in Figure 1. The other end of the anchor bar will have the L-member 12 extending outside of the cast and through the opening 13 thereof the pin 33 on the tensioning and scale unit will be inserted. The pins 46 are 45 now driven through the leg at the proper point and through the ankle. The flexible leg portions of the splint 23 are now snapped over the ends of the pin at the ankle, and the bight 23 of the splint is adjusted on the U-shaped connector 20 and 50 fixed by the bolt and nut detent 47. This adjustment affords the necessary toeing in of the foot incident to the proper reduction of the fracture.

Now with the anchor properly fixed, the splint 55 applied to the bad leg, the bad leg toed in, and the cast applied to the bad leg, all that is required now is to get the proper pull on the fractured leg to absolutely reduce the fracture.

The old method of maintaining fractures under 60 tension was to stretch the fractured leg by suspended weights. In that method, it was very easy to determine how much weight should be applied and the physician in charge always knew just how much weight was employed.

65 However, with the types of fracture reducing apparatus where the good leg is employed for the anchor and a spring is interposed between the anchor and the splint, no means has been devised for efficiently ascertaining the actual tension 70 being employed.

In the present invention, by adjusting the wing nut 42 on the threaded rod 34, the attendant can set the lever 16 at a tension he believes will reduce the fracture and then leave the appliance

with the assurance that there is ample tension to maintain the fracture reduced.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

1. A fracture splint comprising a good leg anchor extending longitudinally on the leg, a bad leg attaching member, a pivotal link connection between the lower end of the anchor and the attaching member, and adjusting means between 15 the anchor at its upper end portion and the intermediate portion of the link.

2. A fracture splint comprising a good leg anchor extending longitudinally on the leg, a bad leg attaching member, a pivotal link connection 20 between the lower end of the anchor and the attaching member, and an extensible adjusting unit interposed between the upper end of the anchor and the intermediate portion of the link.

3. A fracture splint comprising a good leg anchor 25 extending longitudinally on the leg, a bad leg attaching member, a pivotal link connection between the lower end of the anchor and the attaching member, and adjusting means between the anchor at its upper end portion and the intermediate portion of the link, said adjusting means consisting of a barrel connected at one end to the anchor, a rod extending into the barrel and provided with threads, and a spring interposed between the nut and the adjacent end of the 30 barrel, said rod being attached at its outer end to the intermediate portion of the link.

4. A fracture splint comprising a good leg anchor 35 extending longitudinally on the leg, a bad leg attaching member, a pivotal link connection 40 between the lower end of the anchor and the attaching member, and adjusting means between the anchor at its upper end portion and the intermediate portion of the link, said adjusting means consisting of a barrel connected at one 45 end to the anchor, a rod extending into the barrel and provided with threads, and a spring interposed between the nut and the adjacent end of the barrel, said rod being attached at its outer end to the intermediate portion of the link, said 50 barrel at the last mentioned end portion thereof being provided with scale readings, and a slide on said end of the barrel actuated by the nut in complement with said scale readings.

5. In a fracture splint comprising a good leg 55 anchor extending longitudinally on the leg, a bad leg attaching member, a pivotal link connection between the lower end of the anchor and the attaching member, and adjusting means between the anchor at its upper end portion and the intermediate portion of the link, said means including a scale for determining the tension imposed on the said link.

6. A fracture splint comprising a good leg anchor, a cast for affixing the good leg anchor to 65 the foot portion of the good leg, said good leg anchor provided with an extension disposed for a substantial distance through the cast to terminate adjacent the knee of the good leg, a bad leg anchor, a pivotal link between the said anchors and adjusting means between the intermediate portion of the link and the knee end of the good leg anchor extension.

CREED A. WILTROUT.
